UNITED STATES PATENT OFFICE.

JOHN L. TAYLOR, OF CHICAGO, ILLINOIS, ASSIGNOR TO TAYLOR PORTABLE STEEL DERRICK COMPANY, A CORPORATION OF ILLINOIS.

GONDOLA DERRICK.

1,111,415.

Specification of Letters Patent. Patented Sept. 22, 1914.

Application filed August 27, 1913. Serial No. 786,986.

To all whom it may concern:

Be it known that I, JOHN L. TAYLOR, a citizen of the United States, residing at Chicago, in the county of Cook and State 5 of Illinois, have invented certain new and useful Improvements in Gondola Derricks; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in platforms for attachment to gondola cars and adapted to support derricks when loading and unloading a car.

The invention comprises various details 20 of construction and combinations and arrangements of parts which will be herein-after fully described, shown in the accompanying drawings and then specifically defined in the appended claims.

25 I illustrate my invention in the accompanying drawings, in which:

Figure 1 is a side elevation showing the application of my platform to a gondola car. Fig. 2 is an enlarged detail sectional view through a part of the platform and the wall of the car to which it is fitted. Fig. 3 is a vertical sectional view through the platform and adjusting bracket, the two being 30 disassembled. Fig. 4 is a bottom plan 35 view of a portion of the platform. Fig. 5 is a detail perspective view of a clamping bracket member. Fig. 6 is a sectional view transversely and vertically through the platform and bracket member. Fig. 7 is a 40 top plan view of the platform showing in top plan the edge of the car to which it is fastened, and Fig. 8 is a side elevation of a portion of the wall of the car with the bracket attached thereto.

45 Reference now being had to the details of the drawings by letter, A designates the side wall of a gondola car having the usual truss rods B underneath the same.

C designates the derrick platform, made 50 preferably of metal and having ribs D projecting from the under surface thereof, and upon which platform is the hollow post E of a derrick, the superstructure of which is cut away as it forms no part of the present 55 invention, and to the upper surface of

which platform brace bars F are fastened and which are also broken away and which are adapted to brace said derrick post.

Projections C', integral with the bracket members H, are adapted to rest upon the upper edge of the side wall of the car and the under surfaces of said projections are serrated as at L', while an upright face of the bracket H is designed to bear against the inner face of the car and the channel iron K against the outer face of the side wall of the car. Bracket members N are fastened to said beams K, by means of bolts N', and each is provided with ribs N² upon its upper surface and which are parallel to each other and the upper surface of said members N intermediate the ribs and the edges of the bracket members are provided with series of serrations P which are adapted to engage the teeth L' formed upon the under surface of said forwardly projecting portion C' upon either side of the slot C² therein, as shown clearly in Fig. 4 of the drawings. A bolt O passes through the bracket member N, the head of said bolt engaging the under surface of said bracket member and the shank portion thereof being adapted to pass through one of said slots C² and to receive a winged nut O'. Said ribs N² upon the bracket member N 80 are adapted to engage the spaces C⁴ intermediate the ribs C' which are formed on the under surface of the platform. The bracket members N and said extensions H upon the under surface of the platform 85 serve to coöperate with each other to adjust and hold the platform upon the walls of different thicknesses of gondola cars, the teeth upon the bracket member intermeshing with the teeth upon the under surface 90 of the platform, as will be understood.

The braces Q are held at their lower ends by means of bolts Q' to the channel beams K and having a loose fit, and bolts Q² are passed through the upper ends of 100 the braces and passed through the ribs D of the platform, their heads being countersunk in the upper surfaces thereof.

It will be understood that the channel irons K are of such thickness that the 105 flanges thereon are sufficiently narrow so as to allow said irons to yield to compensate for the adjustment of the brackets to varying widths of walls of gondola cars upon which it may be desired to mount the 110

derrick, this adjustment being further made possible by having a loose joint between the lower ends of the braces Q and the channel irons K.

5 A rod, designated by letter M, has a head M' which is countersunk in a hole in the platform and its threaded portion engages a threaded aperture in the turn buckle M² and also a winged nut M³. Said turn buckle 10 carries a pin R to which one end of the chain R' is fastened, the other end being adapted to engage over one of the truss rods B. Other rods, designated by letter R², have their heads countersunk in the 15 platform and are connected with the turn buckles R³ which in turn are connected through the medium of the chains R⁴ with one of said truss rods B. By the provision of the rods with chains attached thereto 20 and secured as illustrated, means is afforded for securely holding and bracing the platform when adjusted for use upon the side of a car.

The operation of my improved derrick 25 platform apparatus for gondola cars will be readily understood and is as follows:— The brackets upon the platform are placed against the inner surface of the side wall of the car and the angle beam with the 30 bracket members fastened thereto placed against the outer face of the wall of the car and the platform held in an adjusted position by the interlocking teeth upon said bracket member and the under surface of 35 the platform by the turning of the winged nuts upon the bolts O. The chains form means for holding the platform securely to the truss rods upon the truck of the car, as shown.

40 What I claim to be new is:—

1. A derrick platform for gondola cars comprising a platform having downwardly projecting bracket portions for engagement over the upper edge of the side wall of a 45 car and a horizontally extending rib portion serrated upon its under edge, channel beams, braces connecting the lower portions of the latter with said platform, a bracket member fastened to each channel beam and

having serrations upon the upper edge 50 thereof adapted to grip serrations upon the under edges of the ribs upon the platform, and means for holding the serrations in interlocked relation, as set forth.

2. A derrick platform for gondola cars 55 comprising a platform having downwardly projecting bracket portions with a forwardly extending reinforcing rib having serrations upon the lower edge thereof, a channel beam adapted to coöperate with 60 the bracket portion for engagement with the opposite walls of the side of a car, a brace connecting said channel beam and the outer portion of the platform, a bracket member having ribs projecting from the upper horizontal face thereof and designed for engaging grooves in the lower edges of the ribs underneath the platform, and clamping means for holding the serrations upon the bracket member and ribs in locked 65 relation with one another, as set forth.

3. A derrick platform for gondola cars comprising a platform having downwardly projecting bracket portions with a forwardly extending reinforcing rib having an elongated slot and serrations upon the under surface thereof and a groove adjacent thereto, a channel beam having brace connections between the same and the platform, an adjustable bracket member with 80 ribs upon the upper horizontal face thereof adapted to engage said grooves and having serrations adjacent to said ribs and designed to engage the serrations upon said forwardly extending part of the rib underneath the platform, clamping means for holding the adjustable bracket member and channel beam in adjusted positions, and stay chains and rods connected to the platform and adapted to be fastened to a part of 85 90 the car, as set forth.

In testimony whereof I hereunto affix my signature in presence of two witnesses.

JOHN L. TAYLOR.
